UNITED STATES PATENT OFFICE

CARL E. PEDERSEN, OF SAN FRANCISCO, CALIFORNIA, ASSIGNOR TO THE GLOBE-WERNICKE COMPANY, OF CINCINNATI, OHIO, A CORPORATION OF OHIO

MAP ROD

Application filed September 13, 1927. Serial No. 219,204.

My present invention relates to a device for filing and storage purposes and more particularly to an improved form of rack such as is used in supporting tracings, blue-prints and maps in a hanging position.

An object of my invention is to provide a rack adapted to the above use which will not sag under its normal load, and which will be practical, strong, and at the same time occupy a minimum of space.

Other objects and novel features of my invention will appear from the following description taken in connection with the accompanying drawing, in which—

Fig. 1 is a perspective view of a cabinet equipped with a rack in accordance with my invention.

Fig. 2 shows a modified application of my invention.

Fig. 3 is a perspective view of the rack portion alone.

Fig. 4 shows a tab suitable for use with my device.

Fig. 5 shows a rider or spacer adapted to my improved rack.

Fig. 6 is a fragmentary enlarged view of the rider shown in Fig. 5.

Fig. 7 is a fragmentary enlarged sectional view showing the manner of attaching the compression members to the frame.

In Fig. 1 of the drawing, I have shown a steel cabinet and have designated the same by the numeral 10. This cabinet 10 has doors 11 which, when closed, provide a substantially fire and dust proof enclosure. Arranged in the top of the cabinet 10, I show a rack 12 having rods 13 from which are suspended maps or prints 14. From this figure of the drawing, it will be seen that the prints 14 hang free and can, as a result, be filed away without rolling or folding as is usually the case. This method of filing has been found to be the most desirable as it permits storage without wear incident to folding and rolling and as a result preserves the life of the prints and maps. This arrangement also provides for a greater filing space than is the case where drawers or shelves and the like are provided in a cabinet.

The applicant, prior to his present inven-

tion, has constructed a great many filing devices of this character by securing the rods 13 to the sides of the cabinet 10, but he has found this method of supporting the rods 13 to be unsuccessful because of his inability to get sufficient rigidity in the cabinet to prevent distortion as a result of the tension necessary to prevent excessive sagging of the rods 13. He has also found that such a construction puts a strain upon the cabinet which causes it to become distorted so that operation of the doors 11 is interfered with.

In order to overcome these difficulties, the applicant has provided a rack element having the features shown in Fig. 3, but not necessarily limited to the precise construction. This rack comprises end members 15 which in the drawing are shown as of channel iron. The end members 15 are spaced apart by compression rods 16 which have a shoulder bearing against the inner side of the channel iron 15 and are riveted in place. Equally spaced and alternately in a line with the compression rods 16 are the aforementioned support or tension rods 13. The rods 13 pass through the web of the channel iron members 15 and have nuts 17 threaded upon their ends so that they can be put under tension. The compression rods 16 are of a greater diameter than the tension rods 13 and as the rods 13 are tightened, the rods 16 will be placed under compression, thus bringing the end channel members 15 into intimate contact with the shoulders upon the rods 16 and as a result producing a rigid frame which may be placed on brackets or cleats in the cabinet 10 like an ordinary shelf, the channel irons 15 resting upon the brackets. With such a construction, it will be seen that my improved rack can be readily placed in or removed from the cabinet without difficulty and without mutilating the cabinet. By arranging the rods 13 and 16 alternately applicant is able to produce a much lighter frame than would be the case if all the tension members were arranged between a single pair of compression members. Another feature of this construction is that the tension can be increased upon any of the rods 13 without, as a result, causing a loosening of the other rods.

It should also be noted that the nuts upon the ends of the tension rods 13 are concealed inside the channel of the end members 15 thus producing a straight unobstructed outer edge 5 upon the rack. It should also be noted that no nuts or washers are required inside of the end members 15 so that a maximum of filing space is provided upon the rods 13.

In Fig. 2 of the drawing, I show a modified 10 arrangement of my invention. In this modification the rack 12 is suspended from a side wall and the only additional elements required are a chain 18 and a bracket 19. The bracket 19 has a notch 20 for engaging one 15 of the tension rods 13 and the chain 18 has a hook 21 which engages another of the tension rods. The chain 18 is also provided with a turn-buckle 22 for leveling the rack.

In using my improved rack the prints or 20 maps to be filed are provided with tabs 23, one of which is shown in Fig. 4. These tabs are of fabric reinforced with cardboard or the like and have one or two flaps 24 which carry an adhesive substance 25 on their inner sides. A 25 hole 26 is provided in the stiffened portion of the tab and a cut 27 is made vertically through the tab from the hole 26. If a print or map is equipped with these tabs it is only necessary to place the cut 27 adjacent the tension rod 13 and press it in place. The rod will then pass through the hole 26 and, as a result of the stiffness of the tab, the print will hang upon the rod. The number of tabs 30 on a print will be determined by its width and/or upon the number or spacing of the tension rods 13. It should be understood that other means might be used instead of the tabs 23. For instance a border might be provided upon the print or map in which the 35 holes 26 and cuts 27 can be placed.

In order to facilitate movement of the maps or prints upon the rods 13, the applicant has provided riders or spacers 28 such as is shown in Figs. 5 and 6. These riders are of hard wood and are provided with notches 29 and 30 which respectively pass over compression rods 16 and tension rods 13. The spacers are placed along the rods 13 at various intervals and when moved along will engage the several 40 tabs and make possible the movement of a great number of maps at one time. By referring to Fig. 6 of the drawing, it will be seen that the notches 29 are so located that the rider rests upon the rods 16 and the 45 notches 30 are sufficiently large to prevent the rider from touching the rods 13. It will also be noted that the slots 30 on the end of the rider are slightly larger and offset so that if the rider is once snapped into place, it cannot 50 accidentally rise up or become displaced.

From the above it will be seen that I have produced a novel and desirable improvement in filing devices of the type disclosed. Having now described my invention and having 55 shown by way of illustration the preferred

embodiment thereof, I desire to have it understood that I do not limit myself thereto, but aim in the appended claims to cover all modifications which come within the spirit and scope thereof.

Having thus described my invention, what I claim and desire to secure by Letters Patent is—

1. A rack of the character described, comprising end members, compression members for spacing said end members, tension rods alternately arranged with said end members for receiving a series of sheet supporting clips, said tension rods being more numerous than said compression members so that they will serve to support the outer edges of the filed matter engaged by said clips.

2. A rack of the character described comprising end members, compression members for spacing said end members, and tension rods extending between said end members from which to suspend matter to be filed, one of said tension rods being disposed forwardly of the rack with relation to the compression rods.

3. A device of the class described comprising a rack structure, a series of parallel support rods mounted in said rack for receiving a series of sheet supporting clips, and a rider slidably mounted with relation to the rack, said rider having recesses formed therein embracing said support rods, said recesses being substantially larger than the cross section of said rods to permit of twisting of the rider with relation to the rods.

4. A device of the class described, comprising a rack structure, a series of parallel support rods mounted in said rack for receiving a series of sheet-supporting clips, and a rider having sliding engagement with said rack and embracing but not bearing on said rods at right angles thereto for sliding the sheet clips on the rods.

5. A device of the class described, comprising a rack structure, a series of parallel support rods mounted in said rack for receiving a series of sheet supporting clips, and a rider having sliding engagement with said rack and embracing but not bearing on said rods at right angles thereto for sliding the sheet clips on the rods, said rider cut away downwardly adjacent the rods for removal of the rider upwardly from the rack.

CARL E. PEDERSEN.
